UNITED STATES PATENT OFFICE.

ANDREW M. BITCHKE, OF SAN ANTONIO, TEXAS.

RAILROAD-CROSSING.

1,401,191.

Specification of Letters Patent. Patented Dec. 27, 1921.

Application filed January 20, 1899. Serial No. 352,708.

To all whom it may concern:

Be it known that I, ANDREW M. BITCHKE, a citizen of the United States, residing at San Antonio, in the county of Bexar, State 5 of Texas, have invented a new and useful Railroad-Crossing; and I do hereby declare the following to be a full, clear, and exact description of the invention, such as will enable others skilled in the art to which it 10 appertains to make and use the same.

The invention relates to roads and more particularly to roads which cross railroad tracks in rural districts and has for its object to provide barriers at each side of the 15 track and spaced therefrom and so positioned that a vehicle approaching the track will be compelled to slow down and follow a circuitous road bed around the barrier so that the vehicle will have to be so positioned 20 that the operator will get a clear view up and down the track, thereby reducing the possibilities of accident caused by the rapid approach of an unseen train.

A further object is to provide a railroad 25 crossing comprising a road crossing the tracks at substantially a right angle and to provide barriers on each side of the track and substantially parallel therewith, said barriers being wider than the road bed so 30 that vehicles approaching the track will have to pass around the ends of the barriers over portions of road which are parallel with the track so that the vehicle will as it 35 approached the crossing be compelled to point up the track and down the track in its course to the track, thereby causing the operator to have a clear view up and down the track before it actually reaches the point of crossing.

With the above and other objects in view the invention comprising further features and combination and arrangement of parts as hereinafter set forth, shown in the drawings, described and claimed, it being understood 45 that changes in the precise embodiment of the invention may be made within the scope of what is claimed without departing from the spirit of the invention.

In the drawings:

Figure 1 is a plan view of the crossing.

Fig. 2 is a sectional view taken on line 2-2 of Fig. 1.

Fig. 3 is a sectional view similar to Fig. 2 but showing the use of a seat for a barrier.

Fig. 4 is a sectional view similar to Fig.

2 but showing a line of trees which may be used as a barrier.

Referring to the drawings, the numeral 1 designates a railroad track, which track may be a single or double one and 2 a road which crosses the track. The road 2 on each side of the track and spaced therefrom is provided with extensions 3, which extensions are parallel with the track 1 and are of sufficient width from A to B so that when a barrier 4 is placed across the road 2 and has its ends 5 centrally disposed in the extensions 3, road sections 6 and 7 will be formed parallel with the track 1. Road sections 6 and 7 are connected to each other as at 8 at the opposite ends of extension 3, thereby forming a circuitous passage around the end of the barrier as the vehicle approaches the track 1, no matter which side of the road the vehicle driver approaches the railroad crossing from. It will be seen by referring to Fig. 1 that if the driver approaches in the direction of the arrows a that if he is going at a high rate of speed he will have to slow down so as to make the sharp bends. 30 However, when he enters the road section 6, he will get a clear view down the track in the direction of the arrow b, then when he enters the passage 7 he will get a clear view up the track in the direction of the arrow c 35 immediately after which he turns across the track 1 enters the passage 7 on the other side of the track, which passage 7 leads out to the main road 2 through the passage 6, at which point he will be able to again increase 40 the speed of his vehicle. During the course of the vehicle over the crossing it will be seen that the driver will be placed in a position where he will get a clear view of the track in both directions, which view will be 45 free of obstruction. It will also be seen that in approaching the barrier that it will be absolutely necessary for the vehicle to be reduced to a speed which will make it possible for the driver to easily control the 50 machine in going through the circuitous passages.

In Figs. 1 and 2, the barrier 4 is shown as an ordinary fence. However, it is to be understood that this barrier may be a seat or 55 other obstruction as shown in Fig. 3 and if so desired a barrier formed of trees or bushes 9, as shown in Fig. 4 may be used. It is to be understood that it is not absolutely necessary that the road shall cross the 60

track 1 at a right angle, it may cross at various angles. However, the barriers 4 are always placed parallel to the track 1, so that the passages 6 and 7 on each side of the track 5 will also be parallel with the track 1 so that the vehicle in its passage through the passages 6 and 7 will be pointed up the track at one time and down the track another. When the vehicle is approaching from the opposite 10 direction it follows the arrows *d* and passes through passages 6 and 7 in a similar manner as that set forth above.

The invention having been set forth what is claimed as new and useful is:—

15 A railroad crossing comprising a road crossing a railroad at an angle, said road being provided with a circuitous passage having a plurality of sections in parallel relation to the railroad track, the parallel section adjacent the railroad track being spaced

from the track, said parallel sections of the road compelling the approaching vehicle to assume positions in its course to the railroad track so that the operator will have a clear view up and down the track, the parallel 25 section adjacent the track being spaced from the track allowing the operator to stop the vehicle if a train is approaching at a point spaced from the track, said parallel sections of the road being separated from each other 30 by a relatively narrow barrier thereby causing vehicles to quickly assume positions in the parallel sections.

In testimony whereof I have signed my name to this specification in the presence 35 of two subscribing witnesses.

ANDREW M. RITCHHEY.
